UNITED STATES PATENT OFFICE.

PETER McDONOUGH, OF BRADDOCK, PENNSYLVANIA.

FIRE-ALARM APPARATUS.

1,206,564.

Specification of Letters Patent. Patented Nov. 28, 1916.

Application filed February 16, 1916. Serial No. 78,700.

To all whom it may concern:

Be it known that I, PETER McDONOUGH, a citizen of the United States, residing at Braddock, in the county of Allegheny and State of Pennsylvania, have invented new and useful Improvements in Fire-Alarm Apparatus, of which the following is a specification.

This invention relates to improvements in fire alarm apparatus and has particular application to electrically operated fire alarm apparatus.

In carrying out the present invention, it is my purpose to provide a fire alarm apparatus which may be installed in school-houses, hotels, dwelling houses, office buildings and other structures and whereby an alarm will be sounded in the event of fire in any of the rooms of the protected structure.

It is also my purpose to provide a novel form of circuit closer which will be held normally in circuit opening position and operated to circuit closing position in the event

25 of fire in the vicinity of such circuit closer.

Another object of my invention is to provide apparatus of the class described which will embrace the desired features of simplicity, efficiency and durability, which may 30 be installed and maintained at small cost, which will operate efficiently and effectively for its intended purpose, and which will embody comparatively few parts and these so correlated and arranged as to reduce the 35 possibility of derangement to a minimum.

With the above and other objects in view, the invention consists in the construction, combination and arrangement of parts hereinafter set forth in and falling within the 40 scope of the claims.

In the accompanying drawing: Figure 1 is a diagrammatic view of fire alarm apparatus constructed in accordance with the present invention. Fig. 2 is an enlarged 45 side elevation of one of the circuit closers, partly in vertical section. Fig. 3 is a horizontal sectional view through the circuit closer, parts being shown in top plan.

Referring now to the drawing in detail, 50 1 designates a number of audible signals or other alarms located in appropriate places and connected in series in an electric circuit 2 extending throughout the protected structure and including a suitable source of 55 electrical energy. Connected in multiple in the circuit 2 are circuit closers 3 located in

the respective rooms or compartments of the protected structure.

In accordance with my present invention, each circuit closer 3 comprises a base plate 60 4 secured to the wainscoting of the particular compartment or to any other suitable support, and a substantially U-shaped frame 5 having the extremities of the legs thereof outturned as at 6 and fastened to the base 65 plate 4 by means of screws 7 or other suitable fastening devices. Mounted upon the base plate 4 centrally of the frame 5 is a disk 8 and secured to the disk 8 is one end of a coiled expansion spring 9 having the 70 remaining end thereof adapted to engage the central member of the U-shaped frame 5. Extending between certain coils of the spring 9 is an inflammable strip 10 having the ends thereof fastened to the base plate 4 75 by means of tacks 11 or other appropriate securing devices. This inflammable strip 11 acts to hold the outer end of the spring 9 normally out of engagement with the frame 5.

In practice, the frame is connected to one leg of the circuit 2 that extends throughout the protected structure, while the spring 9 is connected to the other leg of such circuit and in the event of fire in the vicinity of 85 any one of the circuit closers, the inflammable strip 10 burns and releases the spring 9 of the particular circuit closer and this spring reacts and engages the central member of the frame 5, thereby bridging the legs 90 of the circuit 2 and energizing the signals.

It will be understood, of course, that as many circuit closers as desired may be used in each compartment of the protected structure and arranged in the most advantageous 95 positions, while the signals 1 may be located in various places so as to notify the proper authorities in the event of fire.

While I have herein shown and described the preferred form of my invention by way 100 of illustration, I wish it to be understood that I do not limit or confine myself to the precise details of construction herein described and delineated, as modification and variation may be made within the scope of 105 the claims and without departing from the spirit of the invention.

I claim:

1. In a fire alarm system, a circuit closer adapted to control an alarm circuit and 110 comprising a base plate, a substantially U-shaped frame having the ends of the legs

thereof outturned and secured to said base plate and adapted to be connected to one side of the controlled circuit, a spring contact arranged within said frame and adapted to be connected to the other leg of the controlled circuit, and inflammable means holding said spring contact normally out of engagement with said frame.

2. In fire alarm apparatus, a circuit closer adapted to control the alarm circuit and comprising a base plate, a frame mounted upon the base plate and connected to one of the legs of the controlled circuit, a coiled spring contact arranged within said frame and secured to said base plate and adapted to be connected to the other leg of the controlled circuit, and an inflammable strip secured to said base plate and passed through certain

coils of said spring to hold the latter normally out of engagement with the frame. 20

3. In fire alarm apparatus, a circuit closer adapted to control the alarm circuit and comprising a U-shaped frame adapted to be connected to one leg of the controlled circuit, a coiled expansion spring within the frame, a disk supporting said spring, and an inflammable strip passed through certain coils of the spring and acting to hold the latter normally out of engagement with said frame. 25

In testimony whereof I affix my signature in presence of two witnesses.

PETER McDONOUGH.
